UNITED STATES PATENT OFFICE.

ALBERT R. LAUBSCHER, OF BRIDGEPORT, CONNECTICUT.

MICROMETER-GAGE.

1,228,791.

Specification of Letters Patent.

Patented June 5, 1917.

Application filed August 4, 1916. Serial No. 113,123.

To all whom it may concern:

Be it known that I, ALBERT R. LAUBSCHER, a citizen of the United States, and resident of Bridgeport, in the county of Fairfield and State of Connecticut, have invented certain new and useful Improvements in Micrometer-Gages, of which the following is a specification.

This invention relates to combined micrometer and measuring tools such as are used by machinists, tool-makers and the like.

The object of the invention is to provide an improved form of tool for metal working, whereby thousandths and fractions of thousandths of an inch, may be readily measured and determined; further to provide a tool for the above purpose which will be particularly accurate and easily operated; to construct the device in a substantial yet relatively simple manner, and finally to provide a tool of the above class which can be adjusted from time to time to take up such wear as may occur and so as to insure accuracy in operation.

With these and other objects in view the invention resides and consists in the construction and novel combination and arrangement of parts hereinafter more fully described, illustrated in the accompanying drawings, and pointed out in the claim hereto appended, it being understood that various changes in the form, proportion, size and minor details of construction within the scope of the claim may be resorted to without departure from the spirit or sacrificing any of the advantages of the invention.

Similar characters of reference denote like or corresponding parts throughout the several figures of the accompanying drawings forming a part of this specification, and upon which,

Figure 1 shows a side elevation of my improved micrometer gage complete.

Fig. 2 is a plan view of the same.

Fig. 3 is a central vertical longitudinal section.

Fig. 4 is a detached side elevation of the nut and shank carried by the adjusting screw and

Fig. 5 shows a side view of a scribing attachment which is adapted to be used in connection with the gage.

Referring in detail to the characters of reference marked upon the drawings 10

represents the body of the instrument, 11 an attachable base which may or may not be used in connection with the body by screws 12. This base is preferably made wider 60 than the body as will be noted from Fig. 2 and is designed to be used in connection with heavy work.

The top edge portion of the body is finished off at an angle with respect to the 65 ends of the body forming an inclined surface 13. This top inclined edge portion is cut out to form a guideway 14, to receive the slide block 15, and to form a finished recess 16 to accommodate the adjusting 70 screw 17. Ribs 18-18 are formed in the side walls of the recess against which the under side of the slide block and the top bearing surface of the nut 20 slidably operate.

The block 15 is provided with an inclined and ribbed bottom surface which is smoothly finished to fit and slide upon and in the top surface of the body, and is adapted to be drawn back and forth and up and down 80 upon the body by the operation of the screw 17 before mentioned. This block is provided with a graduating mark upon one side, that is designated by 0 and which is made to register with any one of the series 85 of graduations upon the side of the body as shown in Fig. 1, and indicated by the numerals 1, 2, 3, 4 and 5.

The screw 17 is mounted in a bearing 21 that is fitted in the upper end of the body 90 and in alignment with the inclined longitudinal recess formed in the top of the body, and serves to engage the nut 20 that carries the slide block. This bearing is fitted into an end opening in the block and is secured 95 in position by means of a screw 22. An operating handle 23 is secured to the outer end of the screw by means of a pin 24 so as to insure the turning of the screw with the turning of the handle. The peripheral 100 surface 25 of the bearing 21 is provided with a mark 0 as shown in Fig. 1 and the surface of the handle is provided with a series of graduation marks indicated by the numerals 0 to 9 inclusive and which are 105 brought to register with the mark 0 of the fixed bearing. These graduations obviously represent fractions of the graduation marks on the side of the body and are used to determine very fine measurements with relation to the said graduations.

The pin 26 seated in the top of the slide

block 15 is of standard height and may be interchanged with a longer or shorter pin to take care of the large differences in distances to be measured. In this connection it might be explained that if the tool is used for measuring heights as would be indicated from the position of the instrument shown in the drawings, the measurements would be made from the base of the tool to the top of this pin 26, said distance being lengthened and shortened by the operation of the screw and the movement of the block and its pin up and down the incline. The shank 27 of the nut 20, extends out through a hole in the block and is clamped thereto by means of nuts as shown. The tapered threaded ends of the nut 20 are split as indicated by 29 in Fig. 4 and upon each of these split ends is screwed a small nut 30 that serves for adjusting the nut to the screw, to take up the wear should it occur, and thus insure a prompt response and movement of the nut and slide with the turning of the screw.

25 The scribing attachment shown in Fig. 5 is carried by a post 31, which has its reduced threaded end seated in a hole of the slide block and upon the upper end is secured a clamp 32 that carries an adjustable arm 33 the ends of which are pointed to form a contact point or marker to engage the stock to be scribed. When this scribing attachment is not in use, it may be replaced by the post 34 shown seated in the threaded

hole in the block as indicated in the drawings.

Having thus described my invention, what I claim and desire to secure by Letters Patent, is:

A gage of the class described, comprising a body having an inclined top surface, with a ribbed guideway formed therein, an attached elongated bearing in alignment with the guideway and having a graduation mark indicated thereon, a slide block mounted in the guideway, and having a graduation mark indicated thereon, a screw rotatably mounted in the bearing, a handle attached to the screw and having a series of graduation marks upon its periphery to register with the mark upon the bearing, a split slide nut mounted upon the screw within the body and having a threaded shank that extends through a hole in the slide-block, means to engage the shank for clamping the block to the body, nuts upon the split slide nut to take up wear and tighten the nut to the screw, a base removably attached to the body, a post carried upon the slideable block, and a scribing attachment carried upon the post.

Signed at Bridgeport, in the county of Fairfield and State of Connecticut this third day of August, A. D. 1916.

ALBERT R. LAUBSCHER.
